UNITED STATES PATENT OFFICE.

WALLER TAYLOR, OF LOS ANGELES, CALIFORNIA.

ORE-PULVERIZING MILL.

SPECIFICATION forming part of Letters Patent No. 761,266, dated May 31, 1904.

Application filed January 13, 1903. Serial No. 138,925. (No model.)

To all whom it may concern:

Be it known that I, WALLER TAYLOR, a citizen of the United States, residing at Los Angeles, in the county of Los Angeles and State 5 of California, have invented certain Improvements in Ore-Pulverizing Mills, of which the following is a specification.

My invention relates to ore-pulverizing mills, and more particularly to pulverizing-mills adapted for use in the reduction of mineral-bearing rock to the fineness requisite to insure the ready separation of the valuable minerals from the gangue.

More particularly, this invention relates to 15 further improvements in the device disclosed in my application, Serial No. 139,924, filed January 13, 1903.

The object of the invention is to provide a 20 pulverizing-mill comprising a revoluble mortar having a crushing-bed upon which crushing-rolls yieldingly bear and in the provision of extending simple, cheap, durable, positive, and efficient means to keep the mortar centered and to guide the mortar in a regular or 25 uniform orbit or path in its revolution, reducing friction in such means to a minimum.

A further object is to provide such means adapted to support the mortar against any side thrust of the mortar-revolving means.

30 Further objects will appear from the detail description of construction and operation.

To these ends the invention consists in the constructions and combinations of parts hereinafter described, and particularly pointed out 35 in the claims, and will be more readily understood by reference to the accompanying drawings, forming part of this specification, in which—

Figure I is a sectional view of an ore-pulverizing mill embodying my invention. Fig. 40 II is a detail plan view of the mortar, mortar-centering ring, and revolving bearing devices therefor. Fig. III is a fragmental plan view of a portion of the mortar, the mortar- 45 centering ring, and one of the revolving bearing and centering devices. Fig. IV is a section on line IV IV, Fig. III.

As shown in the drawings, two series of 50 posts 3 3 and 4 4, equal in number, are arranged in pairs upon a base-plate 2. The

posts 3 3 are located near the center of the plate, while the posts 4 4 are located at the outer edge of the base-plate 2.

5 5 represent boxes in which the ends of the shafts 6 6 are mounted. The boxes 5 5 55 are slidably arranged in their respective posts 3 4 and are supported on springs 11, which rest on stationary supports 12, provided on the respective posts 3 4. Springs 10 bear upon the top of the boxes 5, and their upper 60 ends engage the followers 13, slidingly mounted on the posts and engaged by tension-screws 14, passing through caps 15 at the tops of the posts. The upper extremities of the tension-screws 14 are provided with hand-wheels 16, 65 by which the tension of the springs 10 may be adjusted. The shafts 6 are therefore held in position by a yielding pressure controlled by the tension of the springs 10 11. The pulverizing-rollers 7 are made fast upon the 70 shafts 6. As shown, these rollers 7 are preferably provided with detachable hardened tires or wearing parts 8, attached to the inner body portion 7 by means of locking-keys 9 or other suitable means.

75 Located between the inner series of posts 3 and the outer series of posts 4 is a revoluble mortar 17. This mortar is preferably provided with a detachable bed-plate 18, which is engaged by the roller 7 and forms the pulverizing-surface. This bed-plate 18 is preferably of hardened material. The mortar 17 is supported upon conical rollers 19, engaging a track of corresponding shape formed on the bottom of the mortar, whereby a perfect 85 rolling contact between the rollers and the mortar is formed, thus reducing the friction to a minimum. The rollers 19 are journaled in suitable boxes 20, mounted on a stationary base-plate 2.

90 21 21 represent arms provided with flanges 22, through which bolts 23 pass into the mortar 17, securing the arms thereon. Brackets 24 24 are connected with the respective arms 21, as shown, the connection preferably being by means of a set-screw 25, adapted to pass through the slots 24' in the yoke 28 of the bracket and engaging a threaded opening in the arm 21. The slots 24' are preferably made of sufficient length to provide for the 95 100

necessary adjustment of the brackets 24 on the arm 21. The brackets 24 are attached to the mortar-centering ring 26 by means of suitable bolts 28. This mortar-centering ring 5 is preferably provided with an inclined bearing-face 27.

A series of lugs or projections 29 are formed on the posts 3. These lugs or projections 10 preferably extend between respective pairs of posts 3. Two arms 30 are secured on each lug or projection 29. If desired, these 15 arms may be cast integral with the lugs or projections 29, but are shown in the drawings as bolted thereto. Conical rollers 31 have their shafts 31' mounted in bearings in the 20 arms 30. The pitch of the rollers 31 corresponds to the pitch of the inclined face 27 of the mortar-centering ring.

As the mortar revolves the face 27 bears 25 against the inclined faces 31^a of the rollers 31, the rollers revolving, all friction is avoided, while the ring is held truly centered and caused to revolve in a uniform path or orbit. The inclination of the faces 31^a and 27 aids in 30 supporting the mortar-centering ring and therewith the revoluble mortar.

32 represents a gear by means of which the mortar 17 is revolved. This gear 32 engages a large ring-gear 33, attached to the 35 bottom of the mortar. This gear 32 is fixed on a shaft 34, to the outer end of which is attached a suitable pulley 35, connected in a suitable manner with a suitable motive power. (Not shown.) The shaft 34 is journaled in suitable bearings mounted on the base-plate 2.

The outer wall of the mortar is outwardly inclined, and it extends upwardly from the base-plate, as shown at 17', and is provided with a horizontal ledge 18' of considerable 40 width, beyond which is located a screen 36 of suitable mesh.

A circular amalgamating-trough 37, supported on the posts 4, surrounds the mortar and is arranged to receive the material therefrom as it passes through the screen 36. It is thus seen that I provide simple and efficient means for keeping the revoluble mortar centered and preventing the side thrust of the gear 32, effectuating the lateral displacement 45 of the mortar. It is also seen that any wear may be readily taken up by means of the adjustment of the brackets 24 upon the arms 21.

What I claim, and desire to secure by Letters Patent of the United States, is—

1. The combination, in a pulverizing-mill, of outer and inner series of posts, an annular revoluble mortar located between the two series of posts, said mortar provided upon its 60 bottom with a ring-gear, a driving-gear operating in connection therewith, means for operating said driving-gear, conical rollers supporting said mortar, a mortar-centering ring provided on said mortar, a roller-bearing 65 means provided upon said inner series of posts,

said mortar-centering ring and said roller means provided with coöperating faces oppositely inclined with respect to the mortar-axis and adapted to bear one against the other, whereby said mortar is held against lateral 70 displacement.

2. The combination, in a pulverizing-mill, of outer and inner series of posts, an annular revoluble mortar located between said series of posts, said mortar provided on its under 75 surface with a ring-gear, a driving-gear operating in connection therewith, means for operating said driving-gear, rollers upon which said mortar revolves, said mortar provided with an inwardly-extending mortar-centering 80 ring adjustably secured thereon, said ring provided with a face inclined with respect to the mortar-axis, and a series of conical rollers provided between respective pairs of inner posts, the inclined surface of said mortar-centering ring adapted to bear against the conical 85 faces of said rollers.

3. The combination, in a pulverizing-mill, with a series of inner and a series of outer posts, of an annular revoluble mortar, a mortar-centering ring extending inwardly from said mortar and provided with a contacting face inclined with respect to the mortar-axis, a series of rollers mounted upon said inner 90 series of posts and extending out therefrom, 95 said rollers provided with faces oppositely inclined with respect to the inclined face of said mortar-centering ring adapted to contact with the contacting face of the surrounding mortar-centering ring, means for revolving said 100 mortar, revoluble supporting means for said mortar, and pulverizing-rolls coöperating with said mortar.

4. The combination, in a pulverizing-mill, with a series of inner and a series of outer 105 posts, of an annular revoluble mortar, a mortar-centering ring adjustably secured on said mortar and extending inwardly from said mortar and provided with a contacting face inclined with respect to the mortar-axis, a series 110 of rollers mounted upon said inner series of posts and extending out therefrom, said rollers provided with faces oppositely inclined with respect to the inclined face of said mortar-centering ring adapted to contact with the contacting face of the surrounding mortar-centering ring, means for revolving said 115 mortar, revoluble supporting means for said mortar, and pulverizing-rolls coöperating with said mortar.

In testimony whereof I have signed my name to this specification, in the presence of two subscribing witnesses, at Los Angeles, in the county of Los Angeles and State of California, this 7th day of January, 1903.

WALLER TAYLOR.
